UNITED STATES PATENT OFFICE

2,569,623

STRAP STRETCHING DEVICE

James N. Wognum, Chicago, Ill., assignor to
Acme Steel Company, Chicago, Ill., a corpora-
tion of Illinois

Application February 4, 1948, Serial No. 6,261

20 Claims. (Cl. 254—51)

1

This invention relates to improvements in a strap stretching device adapted for use in drawing taut, around a box or package, a metal strap or binder, preliminary to securing the ends of the strap or binder together.

Many features of the present invention may be employed with particular advantage when embodied in a strap stretching device of the so-called pusher bar type in which one end of the strap is held in fixed relation to the stretching tool by abutting the end of the tool against a metal seal attached to the strap, for example, by threading the strap through a tubular seal and reversely bending the end of the strap, and the strap is then drawn taut by drawing the supply end portion through the seal through the operation of the stretching mechanism. One form of such a device is disclosed in the United States Letters Patent of Frederick A. Endress, No. 2,232,876, dated February 18, 1941.

In the use of prior tools of that type it has been customary to draw out the required length of strap for a particular strapping operation with one hand, while restraining the supply portion with the other hand, and then to thread the strap into the gripping devices of the tool after it has been threaded through a tubular seal and looped around a package. This operation is liable to cut the hand of the operator, particularly when the strap is of very thin gauge and it has the further disadvantage that the strap has to be threaded into the tool on each strapping operation.

In many strap stretching tools, the strap gripping devices are of a type which require the insertion of the strap laterally and these devices are supported only at their inner ends so that the strains set up by the stretching operation tend to spread the outer portions of the gripping devices and thereby cause them to release the outer portions of the strap.

When the strap is gripped by a rotary member which also effects the stretching, it has been customary to employ a circular member having a transversely serrated peripheral surface for engaging the strap and also a separate relatively fixed ratchet wheel having teeth of substantial size controlled by a pawl and detent for rotating the gripping wheel and taking up and holding successively increments of the strap or binder until the strap has been drawn taut. This arrangement has the disadvantage that fine increments of adjustment of the size of the final loop of strap are not possible. When the object to be bound is substantially incompressible, such as a

2

bundle of steel rods or tubes, it frequently happens that the holding detent is riding upon the inclined portion of a ratchet tooth when the most desirable degree of tension has been set up in the strap.

The application of further tension to cause the detent to engage the shoulder of the tooth would break the strap while a release of the tension to cause the detent to engage the shoulder of the preceding tooth would cause the strap to be loose on the bundle. On the other hand, when the package is compressible, it may be damaged by overtensioning the strap in the effort to cause the detent to engage a desired tooth.

One object of the present invention is to overcome the danger of injury to the operator's hand and to insure greater convenience in operation by providing a strap stretching tool having a guide or channel through which the strap is with-

drawn from the source of supply while held in the operator's hand. A further object is to provide a strap stretching tool in which the leading end of the strap is always retained after each strapping operation so that it is not necessary to thread

the strap into the tool until after an entire coil of strapping has been consumed. Another object of the invention is to provide a strap gripping device, capable of use with tools of various types, which is supported at both its inner and its outer ends, whereby a uniform grip is maintained upon the strap throughout its width. Still another object of the invention is to provide a strap stretching tool having strap gripping and stretching means of the rotary type wherein a single finely toothed wheel serves as a strap gripping and feeding device and also as a ratchet wheel, thus simplifying the construction and making it possible to obtain fine increments of adjustment of the tension of a strap so that it

will have the proper relation to the encircled box or package. A further object is to provide improved means for mounting the rotary gripping device and for effecting its release from the strap. Another object of the invention is to provide a simple strap stretching device composed of few parts, many of them metal stampings, which may be economically manufactured. Other objects relate to various features of construction and arrangement which will appear more fully hereinafter.

The nature of the invention will be understood from the following specification taken with the accompanying drawings in which one embodiment is illustrated.

In the drawings,

Figure 1 shows an end elevation of the bale or package having a binding strap passed around it and having the strap stretching device of the present invention in operative relationship to the strap;

Fig. 2 shows the use of the strap stretching device of the present invention in drawing taut a binding strap around a group or bundle of steel tubes or the like;

Fig. 3 shows an enlarged side elevation of the strap stretching device of the present invention with the strap stretching and gripping wheel in its operative position;

Fig. 4 shows a top plan view of the strap stretching device illustrated in Fig. 3;

Fig. 5 shows an end elevation of the improved strap stretching device, looking toward the right as viewed in Figs. 3 and 4;

Fig. 6 shows a bottom plan view of the improved strap stretching device shown in Figs. 3 and 4;

Fig. 7 shows a vertical sectional view taken on the line 7—7 of Fig. 3;

Fig. 8 shows a longitudinal section and partial side elevation on the line 8—8 of Fig. 4, illustrating the use of the device in drawing a strap taut; and

Fig. 9 shows a side elevation of the strap stretching device when the strap gripping and feeding wheel has been elevated from its operative position to permit the threading of a strap into the device.

As illustrated in Fig. 1 of the drawings, the improved strap stretching device 10 is shown in use in applying a metal strap 11 around a bale or package 12. The end of the tool abuts against a tubular metal seal 13 which is attached to the leading end of the strap and the supply portion 11a of the strap, leading from a supply coil or the like, is drawn through the guideway of the tool by the operation of the stretching mechanism.

The use of the strap stretching tool 10 in stretching a metal strap 14 about a bundle of steel tubes or the like 15, is shown in Fig. 2 where the strap is shown as having been operated upon by the tool 10 to the point where it is stretched, i. e., drawn taut, around the bundle of tubes preliminary to deforming the seal 16 and the enclosed strap portion to form an interlocking joint. It is in connection with the binding of this type of bundle that a precise degree of tension in the strap is important in order that the strap may be drawn taut without exceeding the elastic limit of the metal.

As illustrated more particularly in Figs. 3 to 9, inclusive, the improved strap stretching tool comprises a frame or bar 18 which is generally of channel shaped form, being open upon its upper side. At its forward end, this frame is provided with a tip portion 18a having upper and lower walls which converge toward the extremity of the bar, the top wall being formed by flanges 18b which are spaced apart to form a narrow slot 18c, shown in Fig. 4. The walls of the tip portion form a mouth which is slightly wider than the width of the strap and slightly greater in its vertical dimension than the thickness or gauge of the strap. At the rear of the tip portion 18a, the frame or bar 18 is provided with upwardly extending parallel side flanges 18d and, to the rear of these side flanges, the bar or frame is formed of upstanding side walls which are turned inwardly to form top flanges having their edges spaced apart as shown in Fig. 4. There is thus formed a guide channel 19 through which the

metal strap 11 is passed endwise from the source of supply.

In the use of the tool, the supply portion 11a of the strap, drawn from a coil or other source of supply, is threaded through the channel 19 of the bar or frame 18, through the tip portion 18a thereof and thence through the tubular seal 13, after which a loop of the strap 11 is formed around the box or package to be bound and the extremity 11b of the strap is then threaded again through the tubular seal 13 beneath the supply portion 11a of the strap. The extremity 11c of the strap is then reversely bent beneath the seal, as shown in Fig. 8, to form a connection between the seal and the end of the strap which is maintained by the pressure of the seal and strap against the box or package during the binding operation. The extremity of the tip portion 18a of the bar or frame is then caused to abut against one end of the seal 13 as shown in Figs. 1 and 8, whereupon the supply portion 11a of the strap is moved toward the right, as viewed in Figs. 1 and 8, by the operation of the stretching mechanism hereinafter described, thereby drawing the strap taut around the bundle or package.

The side flanges 18d of the bar or frame 18 are provided with enlarged apertures 18f, shown particularly in Figs. 8 and 9, which are loosely engaged by a pin or shaft 20 having its extremities journaled in the side arms 21a of a yoke-shaped bracket 21 which straddles the underside of the member 18 with its arms 21a extending upwardly in parallel relationship to the flanges 18d, as shown particularly in Figs. 4, 5, 6 and 7. The pin 20 is retained in place by U-shaped spring clips 24 which engage annular grooves 20a formed in the ends of the pin outside of the arms 21a. This pin or shaft 20 has journaled thereon between the side flanges 18b of the bar or frame, a circular strap gripping and feeding wheel 22 provided around its periphery with a plurality of very fine and uniformly spaced teeth or serrations 22a which are adapted to coact with the upper surface of a strap seated on the bottom of the channel 19 and also to cooperate with the pawl and detent mechanism hereinafter described in the strap stretching operation.

The toothed wheel 22 is normally maintained in proximity to, but out of engagement with, the top surface of the channel 19 or in contact with the strap if there is a strap seated in that channel, by a leaf spring 23 which is secured to the cross member 21b of the yoke-shaped bracket 21, as shown in Figs. 3, 8 and 9. The member 21 has a tongue 21c which extends forwardly and upwardly beneath the tip portion of a flange 18g which is punched out of the bottom wall of channel 19 as illustrated particularly in Figs. 6 and 8. The leaf spring 23 extends rearwardly from the yoke-shaped member 21 and has its tip seated above another tooth 18h which is punched out of the bottom wall of the channel 19. The downward movement of the wheel 22 is limited by the engagement of the pin 20 with the bottom walls of the apertures 18f, thus holding the teeth 22a out of contact with the bottom wall of the channel 19 when there is no strap in the channel. This spring tends normally to move the cross bar 21b of the bracket 21 upwardly with a corresponding downwardly tilting movement of the forward portions of the arm 21a in which the pin or shaft 20 is journaled, thus carrying the strap gripping and feeding wheel 22 downwardly toward the strap which is seated in the channel 19.

The rotation of the gripping and feeding wheel 22 is effected by a reciprocating lever 25 which is provided at its forward end with parallel side flanges 25a extending on opposite sides of the wheel 22 and between this wheel and the side flanges 18d of the bar or frame 18, as shown particularly in Fig. 7. These side flanges 25a are provided with apertures in which the pin or shaft 20 is journaled and the lever 25 may, therefore, be swung in a vertical plane about the shaft 20 during the operation of effecting rotation of the wheel 22.

In order to make the reciprocation of the lever 25 effective in rotating the toothed wheel 22 in the direction of the arrow 21, the lever is provided with a pawl 28 which is in the form of a substantially flat bar having its end portions seated in triangular-shaped apertures 25b which are formed in the side flanges 25a of the lever. The pawl 28 is rounded at its lower end for engagement with the rounded lower corners of the aperture 25b, and the upper edge of the pawl is provided with a right-angular corner which is adapted to cooperate with the teeth of the wheel 22 in effecting rotation of the wheel when the lever is moved upwardly from the position shown in Figs. 3, 8 and 9. This pawl 28 is normally maintained in engagement with the teeth of the wheel 22 by means of a wire spring 29, shown particularly in Figs. 4, 8 and 9, which is somewhat U-shaped in form with the curved upper extremity 29a thereof bent transversely and hooked over the upper edge of the top flange 25c of the lever. The arms 29b of this spring extend downwardly and beneath the lower edge of the pawl 28 and are thence carried upwardly on the forward side of the pawl and extended through apertures 28a which are formed in the pawl, the extremities 29c of the spring being bent upwardly on the rear side of the pawl so that the normal tendency of the spring 29 is to rock the pawl about its lower edge and toward the toothed peripheral surface of the wheel 22. After an upward movement of the lever 25 with a corresponding angular movement of the wheel 22, a reverse movement of the lever toward its lower position will cause the pawl 28 to slide over the teeth of the wheel 22 in the usual fashion.

After each increment of rotation of the wheel 22 by an upward and forward movement of the lever 25, which is provided at its end with a rounded handle 26 adapted for convenient engagement by the operator, the wheel is held in its advanced position by means of a detent 30 which is in the form of a flat bar similar to the pawl 28 and which has its ends mounted for pivotal movement in triangular shaped apertures 18i which are formed in the side flanges 18d of the bar or frame 18. This detent 30 has a rounded upper edge which is adapted to rock in the rounded upper extremities of the apertures 18i and its lower edge is of angular form adapted to cooperate with the teeth of the wheel 22 to prevent reverse rotation of this wheel after it has been released by the pawl 28. The detent 30 is normally moved into engagement with the teeth 22a by means of a wire spring 31 which is of yoke-shaped form with the yoke portion 31a thereof seated beneath the top flanges 18b of the tip portion of the bar or frame 18, as shown particularly in Figs. 4, 8 and 9. The side arms 31b of this spring extend rearwardly and over the top rounded edge of the detent 30 from which point these arms are bent downwardly and then through apertures 30a which are formed

in the detent, the extremities of the arms of the spring being directed downwardly on the underside of the detent so that the normal action of the spring 31 is to force the lower edge of the detent inwardly into engagement with the teeth 22a of the wheel so that the wheel is held against rotation between successive operations of the lever 25.

When it is desired to thread a strap through the channel 19 and the tip portion 18a of the bar or frame 18, the toothed wheel 22 is elevated from the bottom of the channel in the bar or frame by pressing downwardly on the lever 25 after it has reached the position shown in Fig. 8, thereby causing the lever to rock on the downwardly extending shoulders 25e which are formed on the side flanges thereof to engage the upper surfaces of the bar or frame at opposite sides of the slot 18e. When the lever 25 is rocked on these rounded shoulders 25e, the bracket 21 is tilted and the toothed wheel 22 and the shaft 20 are elevated against the action of the spring 23, thus carrying the toothed wheel 22 upwardly from the position shown in Fig. 8 to that illustrated in Fig. 9, thereby providing a space beneath the toothed wheel through which the strap may be readily threaded. This spaced relation of the teeth of the wheel 22 and the bottom of the channel in the bar or frame 18 may be varied by the tilting of the bracket 21 against the action of the spring 23 in order to accommodate straps of different gauges.

After the strap has once been threaded through the bar or frame 18, it remains in the tool, being held by the spring pressed gripping and feeding wheel 22, until all the coil or other supply of strapping has been consumed, whereupon the leading end of the strap of another coil is pushed through the guide channel 19 and the tip portion 18a after rocking the wheel 22 upwardly to the retracted position shown in Fig. 9.

During the operation of drawing a strap taut around a box, package or bundle, or other object, the strap is moved toward the right through the guide channel of the tool by successive operations of the lever 25, while the free end of the strap is held stationary by the engagement of the seal 13 with the end of the tip portion 18a. The teeth 22a may be made very fine in order to obtain a better grip on the strap and in order to permit very fine increments of adjustment of the tension in the strap. For example, the apices of the teeth 22a may be $\frac{1}{2}$ of an inch or less apart. These teeth are preferably formed so that the opposite sides of each tooth are of equal depth and of the same inclination to a radius of the wheel passing through the apex of the tooth. Because of this possibility of obtaining very fine degrees of adjustment in the tension of the strap, it is possible to obtain a precise degree of tautness in the strap which is suitable for the character of the object being bound.

The primary parts of this strap stretching tool, namely, the member 18, the lever 25 and the yoke-shaped member 21 may preferably be formed as steel stampings, thus simplifying the manufacture of the device and greatly reducing its cost as compared with other forms of strap stretching devices heretofore used.

Although one form of the invention has been shown and described by way of illustration, it will be understood that it may be constructed in various other embodiments which come within the scope of the appended claims.

I claim:

1. In a strap stretching device, a bar having a guide channel adapted to receive and laterally confine a strap, means for gripping said strap in said channel, and means for operating said gripping means to move the strap in said channel.

2. In a strap stretching device, a bar having a channel adapted to receive and laterally confine a strap thrust into the channel endwise, and a gripping member mounted to engage and hold the strap in said channel.

3. In a strap stretching device, a bar having a channel adapted to receive and laterally confine a strap thrust into the channel endwise, a gripping member mounted to engage and hold the strap in said channel, and means for operating said member to effect movement of said strap endwise through said channel.

4. In a strap stretching device, a frame member having means for supporting a strap, a gripping wheel having peripheral teeth adapted to engage and hold said strap, and means having parts engageable with said teeth for effecting rotation of said wheel and thereby causing endwise movement of said strap.

5. In a strap stretching device, a frame member having means for supporting a strap, a gripping wheel having peripheral teeth adapted to engage said strap, means including a spring for causing said wheel to grip said strap, and means engageable with said teeth for rotating said wheel and thereby effecting movement of said strap.

6. In a strap stretching device, a frame member having means for supporting a strap, a gripping wheel having peripheral teeth adapted to engage said strap, means including a spring for causing said wheel to grip said strap, and means including a reciprocating lever and a pawl and detent engageable with said teeth for effecting rotation of said wheel and endwise movement of said strap.

7. In a strap stretching device, a frame member having a guide channel through which a strap may be moved endwise, a gripping member engageable with a strap in said channel, means for actuating said gripping member to effect endwise movement of said strap, and a mount for said gripping member, said mount being actuated by a part of said actuating means for moving said gripping member away from said strap.

8. In a strap stretching device, a frame member having a guide channel through which a strap may be moved endwise, a gripping member engageable with a strap in said channel, means including a spring for moving said gripping member into engagement with said strap, means for actuating said gripping member to effect endwise movement of said strap, and means actuated by a part of said last named means for moving said gripping member away from said strap.

9. In a strap stretching device, a frame member having a guide channel through which a strap may be moved endwise, a gripping member, a bracket resiliently mounted on said frame member, a pivot pin carried by said bracket for supporting said gripping member, and means mounted on said pivot pin for actuating said gripping member to effect endwise movement of said strap.

10. In a strap stretching device, a frame member having a guide channel through which a strap may be moved endwise, a gripping mem-

ber, a bracket, a pin mounted in said bracket and having said gripping member mounted for rotatable movement thereon, means for resiliently mounting said bracket on said frame member to cause said gripping member to engage said strap in said channel, and means for actuating said gripping member to effect endwise movement of said strap.

11. In a strap stretching device, a frame member having a guide for a strap, a gripping wheel having peripheral teeth adapted to engage said strap, a pin on which said wheel is rotatably mounted, a bracket for supporting said pin at both ends, and means for resiliently mounting said bracket on said frame member and causing said teeth normally to engage said strap.

12. In a strap stretching device, a frame member having a guide for a strap, a gripping wheel having peripheral teeth adapted to engage said strap, a pin on which said wheel is rotatably mounted, a bracket extending under the strap for supporting said pin, means for resiliently mounting said bracket on said frame member and causing said teeth normally to engage said strap, means including a reciprocatory lever for rotat- 20 ing said wheel and thereby effecting endwise movement of said strap, and means actuated by an abnormal movement of said lever for moving said wheel out of engagement with said strap.

13. In a strap stretching device, a frame member having a guide for a strap, a gripping wheel having peripheral teeth adapted to engage said strap, a pin on which said wheel is rotatably mounted, a bracket for supporting said pin, means for resiliently mounting said bracket on said frame member and causing said teeth normally to engage said strap, and means including a reciprocatory lever and a pawl engaging said teeth for rotating said wheel and thereby effect- 30 ing endwise movement of said strap.

14. In a strap stretching device, a frame member having a guide for a strap, a bracket mounted on said frame, a gripping member carried by said bracket, a spring attached to said bracket and engaging said frame to cause said gripping mem- 40 ber to move normally into engagement with a strap in said guide, and means including a lever pivotally supported by said bracket for actuating said gripping member to effect endwise movement of said strap in said guide.

15. In a strap stretching device, a frame member having a guide for a strap, a bracket mounted on said frame, a gripping member carried by said bracket, a spring attached to said bracket and engaging said frame to cause said gripping member to move normally into engagement with a strap in said guide, and means including a lever pivotally supported by said bracket for actuating said gripping member to effect endwise movement of said strap in said guide, said lever having a projection adapted to engage said frame upon abnormal movement of said lever to move said bracket with respect to said frame and thereby move said gripping member away from said strap.

16. In a strap stretching device, a frame having a guide channel through which a strap is adapted to pass endwise, a yoke-shaped bracket embracing said frame and having arms extending upwardly on the outer side of said frame, said frame having side flanges located inside of said arms and provided with apertures, a pin mounted in said arms and loosely engaging said apertures, a gripping member mounted on said pin between said flanges, and resilient means

engaging said frame and said bracket for causing said gripping member normally to engage a strap in said guideway.

17. In a strap stretching device, a frame having a guide channel through which a strap is adapted to pass endwise, a yoke-shaped bracket embracing said frame and having arms extending upwardly on the outer side of said frame, said frame having side flanges located inside of said arms and provided with apertures, a pin mounted in said arms and loosely engaging said apertures, a gripping member mounted on said pin between said flanges, and a spring fixed to said bracket and engaging the underside of said frame to effect a pivotal movement of said bracket and thereby a movement of said gripping member into engagement with a strap in said guide.

18. In a strap stretching device, a frame having a guide channel through which a strap is adapted to pass endwise, a yoke-shaped bracket embracing said frame and having arms extending upwardly on the outer side of said frame, said frame having side flanges located inside of said arms and provided with apertures, a pin mounted in said arms and loosely engaging said apertures, a gripping wheel mounted on said pin between said flanges and having peripheral teeth adapted to engage said strap in said guide, resilient means engaging said bracket for causing said wheel normally to engage said strap, a lever pivoted on said pin, a pawl carried by said lever and arranged to engage said teeth for rotating said wheel upon reciprocation of said lever, and a detent mounted on said frame and adapted to engage said teeth to hold said wheel between successive working strokes of said lever.

19. In a strap stretching device, a frame hav-

ing a guide channel and a tip portion provided with a restricted mouth through which a strap is adapted to pass endwise, said mouth having walls adapted to confine said strap along its opposite side edges, and means including a single member located in said channel and having teeth for holding said strap and for effecting endwise movement thereof.

20. In a strap stretching device, a frame having a guide channel and a tip portion provided with a restricted mouth through which a strap is adapted to pass endwise, said mouth having walls adapted to confine said strap along its opposite side edges, a wheel mounted in said channel and having peripheral teeth for engaging said strap, and manually operated means engaging said teeth for rotating said wheel to move said strap through said mouth and said channel.
